[57] CLAIM

The ornamental design for a packaging container or similar article, as shown and described.

DESCRIPTION

FIG. 1 is a side elevational view of a packaging container showing my new design;

FIG. 2 is a top plan view;

FIG. 3 is a sectional view taken along line 3—3 of FIG. 2;

FIG. 4 is a bottom plan view; and

FIG. 5 is a bottom view showing a further embodiment of my new design wherein the only difference is in the bottom shown.

FIG. 1

FIG. 3

FIG. 2

FIG. 4

FIG. 5
